IMPULSE CLUTCH

Delos E. Marsh, Los Angeles, Calif.

Application April 6, 1938, Serial No. 200,362

17 Claims. (Cl. 74—25)

This invention is an impulse clutch and has for its object to apply a driving force to a driven element and then automatically disengage the driving connection after predetermined movement of the driven element.

It is a further object of the invention to limit movement of the driven element at each actuation thereof, and to position the parts for re-engagement of the driving connection at the end of each movement of the driven element.

It is a still further object of the invention to suddenly apply the driving force and to automatically disengage the driving connection after a brief interval of engagement, so as to provide a brief interval of movement for the driven element, at the end of which the parts are again in position for engagement of the driving connection. The invention is thus particularly adapted for applying a series of sudden, intermittent impulses to a driven element, with the series of impulses following one another with great rapidity. The invention may thus be advantageously employed in apparatus operated by and/or controlling sound, light or electrical waves of high frequency.

It is a still further object of the invention to apply a relatively strong driving force to the driven element, and to control engagement of the driving connection by a relatively weak force.

The invention is thus particularly adapted for controlling the driving connection by a force such as a weak electrical current, for actuating the driven element by a relatively strong driving force. The invention may thus be advantageously employed in electrical relays and the like, with a weak line current controlling engagement of the driving connection, which in turn applies a relatively strong force for controlling a local circuit.

It is a particular object of the invention to utilize movement of the driven element for interrupting a beam of light which in turn controls an electrical circuit, thereby controlling the circuit without mechanical engagement and disengagement of electrical contacts in said circuit, and thus providing an extremely sensitive control which is particularly applicable to an electrical relay.

It is a still further object of the invention to 50 positively arrest movement of the driven element upon disengagement of the driving connection, without binding action opposing subsequent re-engagement of the driving connection. The driving connection is thus particularly adapted 55 for control by an extremely weak force and for

ready engagement and disengagement so that the series of impulses imparted to the driven element may follow one another with great rapidity.

Further objects of the invention will be readily understood from the following description of the accompanying drawings, in which:

Fig. 1 is a side elevation of the invention embodied in a photo-electric relay.

Fig. 2 is a plan view of the same.

Fig. 3 is a detail section on the lines 3—3 of Fig. 1.

Fig. 4 is a detail section on the line 4—4 of Fig. 3.

Fig. 5 is a view similar to Fig. 3, showing a modified construction.

Figs. 6 and 7 are detail sections on the lines 6—6 and 7—7 respectively of Fig. 5.

Fig. 8 is a side elevation of the invention, embodied in a modified construction wherein the driven element provides a step-by-step mechanical drive for any desired apparatus.

Fig. 9 is a plan view of that embodiment of the invention which is shown at Fig. 8.

Fig. 10 is a detail section on the line 10—10 of Fig. 9.

Fig. 11 is a plan view of the detail shown at Fig. 10.

Fig. 12 is a vertical section on the line 12—12 of Fig. 10.

The invention is applicable to any apparatus wherein a relatively strong driving force is to be applied for imparting a series of impulses to a driven element, with application of the driving force controlled by any suitable means, e. g. a manual or electro-magnetic control, and with movement of the driven element employed for any desired purpose, e. g. for actuating a shutter, controlling an electrical circuit, causing movement of an indicator, etc.

The invention is particularly applicable to electrical relays, and more particularly a photo-electric relay whereby a weak line current may be employed for controlling application of a relatively strong driving force for actuating a shutter, with the shutter interrupting a light beam which in turn controls a photo-electric cell for making and breaking a local circuit. The invention is also particularly applicable to an electrical indicator whereby a weak line current may be employed for controlling application of a relatively strong driving force for step-by-step rotation of a driven element in accordance with weak impulses in the line circuit, so as to correspondingly actuate an indicator which is operated by the driven element.

The invention embodies a driving element and a driven element, and a driving connection therebetween. The driving element may be driven by any suitable source of power, and in the illustrated embodiments of the invention the driving element is a rotatable element driven by an electric motor. The driving connection may be manually or otherwise controlled, and in the illustrated embodiments of the invention the driving connection is controlled by an electro-magnet. The driving connection is automatically disengaged after predetermined movement of the driven element, with the driven element limited to predetermined movement after said disengagement; and in the illustrated embodiments of the invention this predetermined movement of the driven element is an arc of oscillation, or an arc of step-by-step rotation.

The driving connection is arranged so that after predetermined movement of the driven element the parts are again in position for engagement of the driving connection. An illustrated embodiment of this arrangement includes an oscillating pawl, one end of which is engaged by the driving element for swinging the pawl and the driven element in one direction and then automatically disengaging said pawl-end from the driving element after predetermined arcuate movement of the driven element, with said arcuate movement of the pawl positioning the same ready for engagement of its opposite end by the driving element for swinging the pawl and the driven element in the opposite direction. Another illustrated embodiment includes a pawl, one circumferential portion of which is engaged by the driving element for rotating the pawl and the driven element and then automatically disengaging said pawl from the driving element after predetermined rotation of the driven element, with said rotation of the pawl positioning the same ready for engagement of another portion of the pawl by the driving element for again rotating the pawl and the driven element a predetermined distance in the same direction as that first mentioned.

Movement of the driven element may be employed for actuating any desired mechanism. In an illustrated embodiment, movement of the driven element actuates a control for an electrical circuit and while this control may be of any desired type, such as mechanical engagement and disengagement of electrical contacts, the invention is particularly applicable and is illustrated in connection with a photo-electric control adapted for interruption of a light beam by movement of the driven element, with the light beam controlling a photo-electric cell which in turn makes and breaks an electrical circuit. In another illustrated embodiment, movement of the driven element provides a drive for any desired apparatus, e. g. an indicator which is thus actuated in accordance with impulses imparted to the driven element.

Referring to Figs. 1 to 4, the invention is embodied in a photo-electric relay in which the driving connection is electro-magnetically controlled and the driven element is oscillated for swinging a shutter so as to intercept a light beam which controls a photo-electric cell for making and breaking an electrical circuit. The electrical circuit is thus controlled without mechanically engaging and disengaging electrical contacts in said circuit, and the relay is thus adapted for operation at high frequency and by a weak current for

energizing the electromagnetic control for the driving connection.

As an instance of this arrangement, the driving element is shown as transversely spaced friction discs 1-2 which are fixed for rotation with a shaft 3. The shaft 3 is driven by an electric motor 4. The driven element is shown as a pawl 5 medially pivoted on an arm 6 so that it is positioned between the transversely spaced discs 1-2. The arm 6 is fixed on a shaft 7 which is adapted for oscillation so as to transversely shift the arm for positioning one end or the other of the pawl 5 for engagement by one or the other of the discs 1-2, while at the same time positioning the other end of the pawl so that it clears the other of said discs. The shaft 7 is oscillated by an armature pole piece 8 which is fixed on said shaft and which extends between the pole pieces 9 of electrical coils 10. The coils 10 and a permanent magnet 11 cooperate to form an electromagnet which is included in an electrical circuit (not shown), and which is arranged whereby an alternating current in the circuit oscillates the armature pole piece 8 for transversely shifting the arm 6 so that one end of the pawl 5 is engaged by the driving element each time the current is in one direction, and the other end of the pawl is engaged by the driving element each time the current is in the opposite direction.

Engagement of one end of the pawl by the driving element swings the pawl a limited distance in one direction, and engagement of the other end of the pawl by the driving element swings the pawl a limited distance in the opposite direction. A shutter 15 is fixed to the pawl for oscillation therewith, and its swinging movement in each direction intercepts and then clears a light beam. This light beam may be formed by focusing a source of light (not shown) so as to project a light beam A onto a mirror 16, whereby the beam is reflected as a light beam B which is intercepted by the oscillating shutter 15. The light beam B is directed against a photo-electric cell 17 which is included in an electrical circuit (not shown), whereby the photo-electric cell makes and breaks this circuit each time the shutter 15 is swung in one direction or the other.

The electrical circuit which controls the electromagnet 10-11 may be a weak line current, and the electrical circuit which is controlled by the photo-electric cell 17 may be a local circuit. The weak line current thus controls the local circuit without mechanically engaging and disengaging electrical contacts in said local circuit.

The driving connection between the pawl 5 and the friction discs 1-2 is arranged as follows:

Those portions of the pawl which extend in opposite directions from its medial pivot are angularly disposed as shown at Fig. 3, and the ends of the pawl comprise angularly projecting friction-ends 20-21 adapted to respectively engage similarly angularly disposed friction surfaces 22-23 of the discs 1-2. When the pawl has been swung to a position where its end 20 is substantially normal to but spaced from its cooperating disc 1, and the arm 6 is then transversely shifted to the left as viewed at Fig. 3, the pawl-end 20 is moved into engagement with the friction surface 22 of the disc 1 and the pawl-end 21 is moved clear of its cooperating disc 2 so that it is free to swing without engaging said disc. The resulting driving connection 22-20 swings the pawl 5 on its medial pivot to the position shown at Fig. 3, by rotation of the driving element 1-2 in the direction indicated 75

5 by the arrow C. During this swinging movement the contacting surfaces 22-20 tend to disengage due to the curvature of the surface 22 and the arcuate swing of the pawl-end 20, but continued transverse shifting of the arm 6 causes the pawl-end 20 to overlap the cooperating friction surface 22 as shown at Fig. 4, so as to compensate for this tendency and thus maintain the driving engagement.

10 Adjustable stops 24-25 are provided at the respective sides of the arm 6, and the stop 24 provides a predetermined limit for the aforementioned transverse shifting of said arm. The driving force which has been imparted to the 15 pawl-end 20 then continues swinging movement of said pawl-end, as a result of which the cooperating surfaces 22-20 are automatically disengaged after any desired interval of engagement as determined by adjustment of the stop 24.

20 Adjustable stops 26-27 are provided for the respective pawl-ends 20-21, and the stop 26 limits swinging movement of the pawl-end 20 after the driving connection has been thus disengaged, whereby adjustment of the stop 26 provides any 25 desired limit for the swinging movement of the pawl. The pawl-end 20 is then held against swinging movement in the reverse direction, since any such tendency would reengage the driving connection 22-20 and thus again swing 30 said pawl-end clear of its cooperating driving disc.

35 The limited swinging movement of the pawl-end 20 as thus described and as shown at Fig. 3, swings the opposite pawl-end 21 in the reverse direction to a position substantially normal to but spaced from its cooperating disc 2, ready for engagement of the pawl-end 21 with the friction surface 23 of its cooperating disc 2 when the arm 6 is then transversely shifted to the 40 right as viewed at Fig. 3. When the arm 6 is thus shifted to the right, the pawl-end 20 is moved clear of its cooperating disc 1 so that it is free to swing without engaging said disc, and the driving connection 23-21 then swings the 45 pawl in the direction opposite to that previously described, with continued transverse shifting of the arm 6 maintaining the driving connection 23-21 as previously described, until the arm 6 engages the stop 25. The driving connection is 50 then automatically disengaged as previously described, and swinging movement of the pawl is then arrested by the stop 21. The pawl is then held against reverse swinging movement, since any such tendency would reengage the driving 55 connection 23-21 so as to again swing the pawl-end 21 clear of its cooperating disc 2.

60 The limited swinging movement of the pawl-end 21 as thus described, swings the opposite pawl-end 20 in the reverse direction to a position substantially normal to but spaced from its cooperating disc 1, ready for reengagement of the driving connection 22-20 when the arm 6 is again transversely shifted to the left as viewed at Fig. 3.

65 The pawl-ends 20-21 engage their cooperating stops 26-27 without frictional binding engagement since the pawl-end which has engaged its stop has been swung clear of the friction surface of its cooperating driving disc so as to disengage the driving connection, and consequently movement of the pawl-end is simply arrested by its abutment against its cooperating stop, with no force exerted such as would tend to tightly frictionally bind this abutment. The surfaces 70 75 80 of the pawl-ends which are engaged by the

respective stops are preferably disposed so that the plane of abutment between either pawl-end and its cooperating stop is substantially parallel to the plane of transverse shifting of the arm 6 (as shown by the pawl-end 20 and the stop 26 5 at Fig. 3).

By thus eliminating frictional binding engagement at the abutment of either pawl-end against its cooperating stop, with the abutment in a transverse plane as described, the arm 6 is 10 adapted for transverse shifting to engage the driving connection at the other pawl-end with no binding action opposing its free movement. The arm is thus adapted for rapid transverse shifting by a weak force, thereby adapting the 15 device for imparting a series of impulses to the driven element, with the series of impulses following one another with great rapidity.

When the driving connection 22-20 swings the pawl to the position shown at Fig. 3, the 20 shutter 15 is swung from the position shown by dotted lines to that shown by full lines, and when the driving connection 23-21 swings the pawl in the opposite direction the shutter 15 is 25 swung from the position shown by full lines to that shown by dotted lines. At each swinging movement of the pawl 5 in one direction or the other, the shutter 15 thus intercepts and then again clears the light beam B for actuating the photo-electric cell 17. Each impulse of an 30 alternating current in the circuit which includes the electro-magnet 10-11 and which causes the arm 6 to be transversely shifted in one direction or the other, thus results in a driving force being applied whereby the circuit which is 35 controlled by the photo-electric cell 17 is made and broken in synchronism with the impulses of said alternating current.

The modification of the invention shown at Figs. 5 to 7 may be embodied in the same structure as previously described, but provides a slightly different driving connection between a driving element which is rotated by the shaft 3 and a cooperating pawl 5^a which carries a shutter 15^a and which is medially pivoted on the 45 transversely shiftable arm 6.

40 In this construction, the discs 1^a-2^a are fixed for rotation with the drive shaft 3, but instead of being friction discs as previously described, these discs are toothed ratchet discs. The co- 50 operating pawl 5^a is positioned between the discs 1^a-2^a and its portions which project in opposite direction from its medial pivot are angularly disposed as previously described. The ends 20^a- 21^a of the pawl are adapted for respective en- 55 gagement by the toothed ratchet discs 1^a-2^a when the arm 6 is transversely shifted in one direction or the other. The teeth 30-31 of the respective ratchet discs 1^a-2^a are adjacent the outer peripheries of said discs and project to- 60 ward one another from the inner faces of the respective discs. The teeth have contact surfaces extending an appreciable distance radially of the discs and of gradually increasing width to- 65 ward the outer ends of the teeth as shown at 33 65 at the left of Fig. 6.

The parts are so arranged that when the pawl 5^a has been swung to a position where the pawl-end 20^a is substantially normal to but spaced from its cooperating disc 1^a, and the arm 6 is 70 then transversely shifted to the left as viewed at Fig. 5, the pawl-end 20^a is engaged by a tooth 30 of the disc 1^a, while the pawl-end 21^a is moved clear of its cooperating disc 2^a so that it is free to swing without engaging the teeth 75

of said disc. The resulting driving connection 30—20^a swings the pawl 5^a on its medial pivot to the position shown at Fig. 5, by rotation of the driving element 1^a—2^a in the direction indicated by the arrow C. During this swinging movement, the pawl-end 20^a shifts relative to its cooperating tooth 30 so as to tend to clear the tooth and thus disengage the driving connection, due to the arcuate swing of the pawl-end and the 10 arcuate path of travel of the tooth.

To compensate for this tendency and thus maintain the driving connection, the parts are arranged whereby initial engagement of the pawl-end with a tooth, is at that narrower portion of the tooth which is at the radially inner end of its tooth surface. As the disc 1^a is rotated, the pawl-end 20^a is thus engaged by portions of the tooth surface which are successively further and further from its inner end (due to 15 the arcuate path of travel of the tooth), but the length of the tooth is such as to maintain engagement during this movement. In the same manner, swinging movement of the pawl results in its end 20^a being shifted transversely of the 20 engaged tooth (due to the arcuate swing of the pawl), but the increasing width of the tooth surface toward its outer end, as shown at 33, maintains engagement of the driving connection for an appreciable interval before the pawl-end 20^a is finally swung clear of the tooth 30.

The adjustable stops 24—25 (previously described) limit transverse shifting of the arm 6, and the stop 24 is adjusted so that transverse shifting of the arm provides any desired initial 25 overlapping of the pawl-end 20^a upon a tooth 30, so that swinging movement of the pawl shifts the pawl-end 20^a clear of the edge 33 of the tooth and thus disengages the driving connection, after any desired interval of movement. 30 Adjustable stops 26^a—27^a are provided for the respective pawl-ends 20^a—21^a, and the stop 26^a limits swinging movement of the pawl-end 20^a after the driving connection has been thus disengaged, whereby adjustment of the stop 26^a 35 provides any desired limit for the swinging movement which has been imparted to the pawl by the driving connection 30—20^a. The pawl-end 20^a is then held against swinging movement in the reverse direction, since any such tendency 40 would reengage the driving connection 30—20^a and thus again swing said pawl-end clear of the tooth which has engaged the same.

The limited swinging movement of the pawl-end 20^a as thus described and as shown at Fig. 5, 45 swings the opposite pawl-end 21^a in the reverse direction to a position substantially normal to but spaced from its cooperating disc 2^a, ready for engagement of the pawl-end 21^a by a tooth 31 of its cooperating disc 2^a when the arm 6 is transversely shifted to the right as viewed at Fig. 5. When this driving connection is made, the pawl-end 20^a is moved clear of its cooperating disc 1^a so that it is free to swing without engaging the teeth of said disc, and the driving connection 31—21^a then swings the pawl in the direction opposite to that previously described. Transverse shifting of the arm 6 to provide this driving connection 31—21^a, is limited by the adjustable stop 25, and therefore, as previously 50 described, provides any desired overlapping of the pawl-end 21^a upon the abutment surface of a tooth 31, for swinging the pawl-end clear of the tooth and thus automatically disengaging the driving connection after any desired interval of 55 movement. Upon release of the driving connection, swinging movement of the pawl is arrested by the stop 27^a. The pawl is then held against reverse swinging movement, since any such tendency would reengage the driving connection 31—21^a so as to again swing the pawl-end 21^a clear of the teeth of its cooperating disc 2^a.

The limited swinging movement of the pawl-end 21^a as thus described, swings the opposite pawl-end 20^a in the reverse direction to a position substantially normal to but spaced from its 10 cooperating disc 1^a, ready for reengagement of the driving connection 30—20^a when the arm 6 is again transversely shifted to the left as viewed at Fig. 5.

The abutment of the pawl-ends 20^a—21^a 15 against their respective stops 26^a—27^a produces no frictional binding engagement, the driving connection having been disengaged when such abutment is made so that there is no force tending to bind said abutment, and the surfaces 80^a 20 of the pawl-ends which engage the stops being disposed so that the plane of abutment is substantially parallel to the plane of transverse shifting of the arm 6. The arm 6 is thus adapted for transverse shifting to engage the driving connection at the opposite pawl-end with no binding action opposing its free movement, thereby adapting the device for control by a weak force, and also adapting it for imparting a series of rapid impulses to the driven element.

The pawl 5^a is thus swung in one direction and then the other by transverse shifting of the arm 6 in one direction and then the other; and at each swinging movement of the pawl, the shutter 15^a first intercepts and then clears the light beam B for controlling a photo-electric cell as previously described.

Referring to Figs. 8 to 11, the invention is embodied in a construction in which the driving connection is electro-magnetically controlled as 40 previously described, and the driven element is rotated a predetermined distance at each engagement of the driving connection so as to provide a driving means for any desired apparatus, e. g. an indicator. A step-by-step rotation is 45 thus imparted to the driven element in accordance with the electrical impulses which energize the electro-magnetic control for the driving connection, thereby correspondingly actuating an indicator or the like which is operated by the 50 driven element.

As an instance of this arrangement, the driving element is shown as friction discs 1^b—2^b which are fixed for rotation with a shaft 3^b, the shaft being driven by an electric motor 4^b. The 55 driven element is shown as friction discs 40—41, fixed for rotation with a shaft 42 and defining a peripheral, tapering tongue 43, an arcuate portion of which is adapted for reception in an arcuate portion of a cooperating peripheral, 60 tapering groove 44 which is formed by tapering, peripheral surfaces of the discs 1^b—2^b. The shaft 42 is adapted for axial shifting in one direction or the other, i. e. transversely of the cooperating peripheral tongue and groove 43—44, 65 so that each axial shifting of the shaft engages and then automatically disengages a driving connection at the cooperating peripheral tongue and groove.

The shaft 42 is axially shifted by an arm 6^b 70 which is adapted for transverse shifting by an arrangement the same as that previously described. This construction includes an oscillating shaft 7^b on which the arm 6^b is fixed, with the shaft 7^b oscillated by an armature pole piece 75

8^b which extends between the pole pieces 9^b of an electro-magnet 10^b—11^b. The electro-magnet is controlled by an electrical circuit (not shown), and is arranged so that an alternating current in the circuit oscillates the armature pole piece 8^b for transversely shifting the arm 6^b and thereby axially shifting the shaft 42, so that the driving connection is made and then automatically disengaged each time the current is in one direction, and is then reengaged and again automatically disengaged each time the current is in the opposite direction.

Each engagement of the driving connection rotates the shaft 42 a predetermined limited distance in the same direction; and an operating means, shown as a gear 46 is fixed on the shaft 42 for rotation therewith. Step-by-step rotation of the shaft 42 and the gear 46 thus provides a step-by-step drive for any desired apparatus (not shown), e. g. an indicator which is adapted for movement relative to a cooperating dial. Electrical impulses in the circuit which controls the electro-magnet 10^b—11^b thus cause corresponding step-by-step movement of the indicator or other device which is actuated by the gear 46.

The driving connection at the cooperating peripheral tongue and groove 43—44 is arranged as follows:

Contact surfaces of the discs 40—41 (which define the peripheral tongue 43) are each interrupted by one or more low spots; and the low spots of the respective discs are circumferentially offset relative to one another, so that when the discs 40—41 are turned to a position where a low spot of either one of the discs is received in the groove 44, a non-interrupted portion of the contact surface of the other disc is received in said groove. The number of low spots on the discs 40—41 determine the arc of step-by-step rotation of the shaft 42 at each engagement of the driving connection, and such number of low spots may be employed as to provide any desired arc of rotation. In the illustrated embodiment, the shaft 42 is adapted for rotation through an arc of 90° at each engagement of the driving connection. For this purpose a pair of diametrically opposite low spots 48 are provided on the disc 40, thereby defining a pair of arcuate contact surfaces 50, and a pair of diametrically opposite low spots 49, which are circumferentially offset 90° relative to the low spots 48, are provided on the disc 41, thereby defining a pair of arcuate contact surfaces 51.

Stops are provided for arresting rotation of the shaft 42 each time one of the low spots 48 or 49 is received in the groove 44, and said stops are arranged so as to again release the shaft 42 for further rotation when the arm 6^b is next transversely shifted. In the illustrated embodiment, two of these stops are provided as shown at 52—53, and are spaced axially of the shaft 42 and are fixed for rotation therewith. The stops are mounted on the shaft 42 medially of their length so that each projecting end of each stop forms a stop element, and the stops 52—53 are circumferentially offset 90° from one another.

The arm 6^b is adapted for transverse shifting between the stops 52—53, below the shaft 42. When the arm is transversely shifted in one direction as shown at Fig. 11, it clears the stop 53 and one end or the other of the stop 52 is adapted to rest upon the arm for arresting rotation of the shaft 42, with one or the other of the low spots 48 received in the groove 44; and

when the arm 6^b is transversely shifted in the direction opposite to that shown at Fig. 11, it clears the stop 52 and one end or the other of the stop 53 is adapted to rest upon the arm for arresting rotation of the shaft 42, with one or the other of the low spots 49 received in the groove 44.

A projection 54 at the end of the arm 6^b engages the side of the stop 52 for axially shifting the shaft 42 in the direction indicated by the arrow F, when the arm 6^b is transversely shifted as shown at Fig. 11; and when the arm 6^b is transversely shifted in the opposite direction the projection 54 engages the side of the stop 53 for axially shifting the shaft 42 in the opposite direction. The projection 54 extends above the upper surface of the arm 6^b, so that as the shaft 42 is rotated until one or the other of the stops 52—53 rests upon the arm, the projection 54 maintains pressure against the side of said stop for axially shifting the shaft. The bearings 56 for the shaft 42, permit axial shifting of said shaft, and include stops 57—58 for limiting said axial shifting, with said stops adjustable as shown at 59.

The bearings of the shaft 3^b which carries the friction discs 1^b—2^b are shown at 60, and are preferably yieldable bearings tensioned by springs 61 so as to maintain a friction drive at the tongue and groove 43—44 but adapted to yield for cushioning engagement of said drive. The tension of the springs may be adjusted by bolts 62, and a flexible coupling 63 is provided between the shaft 3^b and the motor 4^b to compensate for yielding of the bearings 60.

Operation of the driving connection 43—44 will be explained, assuming the parts to be in their position opposite to that illustrated at Fig. 11, and in which position the parts are arranged as follows:

The arm 6^b has been transversely shifted in the direction opposite to that indicated by the arrow F, so that the projection 54 has engaged the side of the stop 53 and has axially shifted the shaft 42 in the direction opposite to that indicated by said arrow and to its limit of movement as determined by the stop 58, and the shaft 42 has been rotated in the direction of the arrow G until an end of the stop 53 rests upon the arm 6^b. When the parts are in this position, a low spot 49 of the disc 41 and a contact surface 50 of the disc 40 are received in the groove 44. The disc 41 is thus disengaged from the friction disc 2^b, due to the low spot 49, and the contact surface 50 of the disc 40 is also disengaged from the friction disc 1^b, due to the axially shifted position of the shaft 42. The driving connection is thus disengaged and the shaft 42 is stationary at a limit of rotary movement determined by abutment of the stop 53 against the arm 6^b.

When the arm 6^b is then transversely shifted to the position shown at Fig. 11, it clears the stop 53, and its projection 54 engages the side of the stop 52 so as to axially shift the shaft 42 in the direction of the arrow F. That portion of the contact surface 50 of the disc 40 which is in the groove 44 is thus engaged by the disc 1^b so as to provide a frictional driving connection, engagement of which is cushioned by the springs 61, and whereby rotation of the discs 1^b—2^b in the direction of the arrow H, then rotates the discs 40—41 and the shaft 42 in the direction of the arrow G. The low spot 49 of the disc 41 which is in the groove 44 is thus swung clear of said groove and a portion of a contact surface 51 of said disc is received in said groove and is engaged by the disc 75.

2^b, while the contact surface 50 of the disc 40 is still engaged by the disc 1^b. Rotation of the shaft 42 is thus continued until a low spot of the disc 40 enters the groove 44, which will be just 5 prior to 90° rotation of the shaft 42.

Continued transverse shifting of the arm 6^b then continues axial shifting of the shaft 42 in the direction of the arrow F, with this continued 10 axial shifting of the shaft made possible by the space which has been formed between the low spot 48 of the disc 40 and the cooperating surface 15 of the groove 44. This continued axial shifting of the shaft disengages the contact surface 51 of the disc 42 from the cooperating surface of the groove 44, but said axial shifting of the shaft is arrested by the stop 57, while the low spot 48 of the disc 40 is still disengaged from the cooperating surface of the groove 44, as shown at Fig. 11. The driving connection between the discs 1^b—2^b and the discs 40—41 is thus disengaged, with said disengagement occurring just 20 prior to completion of 90° rotation of the shaft 42. The driving force which has been imparted to the shaft 42 then continues rotation of the shaft until arrested by the stop 52 engaging the upper surface of the arm 6^b, the parts being relatively arranged whereby the shaft is thus fixed against further rotation when it has been turned exactly 90°, with the low spot 48 of the disc 40 25 and the contact surface 51 of the disc 41 still received in the groove 44. The position of the parts is then as shown at Fig. 11, with rotation of the shaft 42 having rotated the gear 46 through an arc of 90°.

35 The parts are then in position ready for reengagement of the driving connection by transversely shifting the arm 6^b in the opposite direction so as to axially shift the shaft 42 in the direction opposite to that indicated by the arrow F. 40 By such transverse shifting of the arm 6^b, it is moved clear of the stop 52 so that the shaft 42 is again free to rotate, and the contact surface 51 of the disc 41 which is in the groove 44 is thus engaged by the cooperating disc 2^b so as to provide a frictional driving connection, engagement of which is cushioned by the springs 61, and whereby rotation of the discs 1^b—2^b then rotates the discs 40—41 and the shaft 42 in the same direction as that previously described.

50 The low spot 48 of the disc 40 which is in the groove 44 is thus swung clear of the groove and a portion of a contact surface 50 of said disc is received in said groove and is engaged by the disc 1^b, while the contact surface 51 of the disc 55 41 is still engaged by the disc 2^b. Rotation of the shaft 42 is thus continued until a low spot 49 of the disc 41 enters the groove 44, whereupon continued axial shifting of the shaft 42, until arrested by the stop 58, spaces the contact surface 60 59 of the disc 40 and the low spot 49 of the disc 41 from the cooperating surfaces of the groove 44, so as to disengage the driving connection as previously described. Rotation of the shaft 42 is then arrested by the stop 53 engaging the upper surface of the arm 6^b when the shaft has been 65 rotated exactly 90°.

With the shaft 42 thus fixed against further rotation, and with a low spot 49 of the disc 41 and a portion of a contact surface 50 of the disc 40 70 then received in the groove 44, the parts are again in position ready for engagement of the driving connection by transverse shifting of the arm 6^b in the opposite direction, to the position shown at Fig. 11.

75 At each transverse shifting of the arm 6^b in

one direction or the other, the shaft 42 is thus rotated exactly 90° in the direction of the arrow G, thereby providing corresponding step-by-step rotation of the gear 46, for driving any suitable mechanism such as an indicator. Each impulse 5 of an alternating current in the circuit which includes the electro-magnet 10^b—11^b and which causes the arm 6^b to be transversely shifted in one direction or the other, thus results in a driving force being applied, for step-by-step rotation of 10 the gear 46 in synchronism with the impulses of said alternating current, so as to synchronously actuate any desired mechanism which is arranged for operation by the gear 46.

When rotation of the shaft 42 is arrested, one 15 or the other of the stops 52—53 rests upon the arm 6^b without frictional binding engagement since the driving connection which rotates the shaft is then disengaged, and consequently rotation of the shaft is simply arrested by abutment 20 of one or the other of the stops against the upper surface of the arm, with no force exerted such as would tend to tightly frictionally bind this abutment. The upper surface 80 of the arm 6^b, which is engaged by one or the other of the stops, 25 is disposed so that the plane of abutment between the arm and either stop is substantially parallel to the plane of transverse shifting of the arm. By thus eliminating frictional binding engagement at the abutment of either stop against the 30 upper surface of the arm, with the abutment in a transverse plane as described, the arm 6^b is adapted for transverse shifting to control the driving connection with no binding action opposing its free movement, thereby adapting the device for 35 control by a weak force and also adapting it for imparting a series of rotary impulses to the shaft 42, with said series of impulses following one another with great rapidity.

As illustrated by the various modifications 40 which have been described, the invention thus provides for applying a relatively strong driving force for impulse actuation of a driven element in accordance with intermittent engagement of a driving connection, with the intermittent engagement of the driving connection controlled by 45 a series of impulses which may be successive impulses of an electrical current, whereby the driven element is actuated in accordance with the impulses of said current for synchronously actuating 50 any desired mechanism, e. g. a shutter, an indicator, or a control for making and breaking an electrical circuit.

I claim:

1. In combination, a pair of friction discs adapted for rotation on a common axis, means for rotating the discs, a driven element adapted for oscillation on an axis transverse to the axis of rotation of the discs and adapted for shifting transversely of its axis of oscillation and between the friction discs, actuating means for transversely shifting the driven element in one direction or the other for initially engaging one end or the other of the driven element by the proximate friction disc so as to provide a driving connection for turning the driven element, said actuating means continuing said transverse shifting of the driven element subsequent to said initial engagement so as to maintain said driving connection for continuing turning of the driven element, means for limiting 60 said transverse shifting of the driven element whereby the driving connection at the engaged end of the driven element is disengaged responsive to turning of the driven element, and means for arresting turning of the driven element 65 70 75 80 85 90 95 100 105 110 115 120 125 130 135 140 145 150 155 160 165 170 175 180 185 190 195 200 205 210 215 220 225 230 235 240 245 250 255 260 265 270 275 280 9425 9430 9435

upon disengagement of the driving connection, the driven element being arranged so that when its turning is arrested upon disengagement of the driving connection at its engaged end its other end is in position ready for engagement by the proximate friction disc upon transverse shifting of the driven element in the opposite direction.

2. In combination, a pair of toothed elements adapted for rotation on a common axis, means for rotating said elements, a driven element adapted for oscillation on an axis transverse to the axis of rotation of the toothed elements and adapted for shifting transversely of its axis of oscillation and between the toothed elements, actuating means for transversely shifting the driven element in one direction or the other for engaging one end or the other of the driven element by a tooth of the proximate toothed element so as to provide a driving connection for turning the driven element, the transverse shifting of the driven element causing its engaged end to overlap the cooperating tooth so as to maintain said driving connection until predetermined turning of the driven element moves its engaged end clear of said tooth so as to disengage said driving connection, and means for arresting turning of the driven element upon disengagement of the driving connection, the driven element being arranged so that when its turning is arrested upon disengagement of the driving connection at its engaged end its other end is in position for engagement by a tooth of the proximate toothed element upon transverse shifting of the driven element in the opposite direction.

3. In combination, a driving element adapted for rotation and having a peripheral groove, means for rotating the driving element, a driven element adapted for rotation on an axis parallel to the axis of rotation of the driving element and having a peripheral tongue adapted for reception in said groove, each side of the peripheral tongue having a contact surface interrupted by one or more low spots, actuating means for axially shifting the driven element in one direction or the other for initially engaging the contact surface at one side or the other of the peripheral tongue with the proximate side of the peripheral groove while a low spot at the other side of the peripheral tongue is received in the peripheral groove in spaced relation from the proximate side thereof, thereby providing a driving connection at the initially engaged side of the peripheral tongue for turning the driven element, said turning of the driven element moving the contact surface at the other side of the peripheral tongue into the peripheral groove for engagement with the proximate side thereof so as to provide a driving connection at said last mentioned contact surface, said turning of the driven element then moving a low spot at the initially engaged side of the peripheral tongue into the peripheral groove for spacing said side of the tongue from the proximate side of the groove and thereby disconnecting the driving connection at said side of the peripheral tongue, the aforesaid actuating means continuing said axial shifting of the driven element so as to disengage the driving connection at the other side of the peripheral tongue, means for limiting said axial shifting with the low spot of the initially engaged side of the peripheral tongue remaining spaced from the proximate side of the peripheral groove so as to maintain disengagement of the driving connection at said side of the peripheral tongue, and means for arresting rotation of the driven element upon

such complete disengagement of the driving connection, said means being arranged whereby movement of the aforesaid actuating means for axially shifting the driven element in the opposite direction releases the driven element for further rotation.

4. In combination, transmission elements each adapted for movement, said elements being also adapted for relative shifting distinct from said movement of the elements, a contact surface on one of the transmission elements, actuating means for producing said relative shifting, means for periodically operating said actuating means independently of said movement of the transmission elements, said relative shifting causing engagement of the contact surface on the said one of the transmission elements with the other transmission element, said engagement providing a driving connection for producing said movement of one of the transmission elements by said movement by the other transmission element, the transmission elements being adapted for relative displacement responsive to movement thereof one by the other, and the contact surface being adapted for disengagement from the other transmission element responsive to said relative displacement and independently of said relative shifting, and means operative upon disengagement of the contact surface from the other transmission element for arresting said movement of one of the transmission elements by the other.

5. In combination, transmission elements each adapted for movement, said elements being also adapted for relative shifting distinct from said movement of the elements, a contact surface on one of the transmission elements, actuating means for producing said relative shifting, means for periodically operating said actuating means independently of said movement of the transmission elements, said relative shifting causing engagement of the contact surface on the said one of the transmission elements with the other transmission element, said engagement providing a driving connection for producing said movement of one of the transmission elements by said movement by the other transmission element, the transmission elements being adapted for relative displacement responsive to movement thereof one by the other, the contact surface being adapted for disengagement from the other transmission element responsive to said relative displacement and independently of said relative shifting, abutment means operative upon disengagement of the contact surface from the other transmission element for arresting said movement of one of the transmission elements by the other, and another contact surface on one of the transmission elements adapted for positioning responsive to said relative displacement and said relative shifting, for engagement with the other transmission element responsive to the transmission elements being again relatively shifted, said last mentioned engagement repeating the cycle of operation, and the abutment means being inoperative during repetition of the cycle of operation until disengagement of the last mentioned contact surface from the other transmission element.

6. In combination, transmission elements each adapted for movement, said elements being also adapted for relative shifting in either of opposite directions, with said relative shifting distinct from said movement of the elements, a contact surface on one of the transmission elements, actuating means for producing said relative shift-

- ing, means for periodically operating said actuating means independently of said movement of the transmission elements, the relative shifting in one direction causing engagement of the contact surface on the said one of the transmission elements with the other transmission element, said engagement providing a driving connection for producing said movement of one of the transmission elements by said movement by the other transmission element, the transmission elements being adapted for relative displacement responsive to movement thereof one by the other, the contact surface being adapted for disengagement from the other transmission element responsive to said relative displacement and independently of said relative shifting, abutment means operative upon disengagement of the contact surface from the other transmission element for arresting said movement of one of the transmission elements by the other, and another contact surface on one of the transmission elements adapted for positioning responsive to said relative displacement and said relative shifting, for engagement with the other transmission element responsive to the transmission elements being relatively shifted in the direction opposite to that first mentioned, said last mentioned engagement repeating the cycle of operation, and the abutment means being inoperative during repetition of the cycle of operation until disengagement of the last mentioned contact surface from the other transmission element.
7. In combination, a driving member, a driven member, said members having peripheral elements forming a cooperating tongue and groove, each side of one of said peripheral elements having a contact surface interrupted by one or more low spots, and actuating means for relatively axially shifting the driving and driven members in one direction or the other for initially engaging one or the other contact surfaces with the proximate side of the cooperating peripheral element, while a low spot which interrupts the other contact surface spaces said other contact surface from that side of the cooperating peripheral element which is proximate thereto, thereby providing a driving connection at the initially engaged contact surface for driving the driven member by the driving member, said driving of the driven member by the driving member moving a low spot which interrupts the initially engaged contact surface into position spacing said initially engaged contact surface from that side of the cooperating peripheral element which is proximate thereto, and moving the other contact surface so that it is in position for engagement with that side of the cooperating peripheral element which is proximate thereto.
8. In combination, a driving member, a driven member, said members having peripheral elements forming a cooperating tongue and groove, each side of one of said peripheral elements having a contact surface interrupted by one or more low spots, and actuating means for relatively axially shifting the driving and driven members in one direction or the other for initially engaging one or the other contact surfaces with the proximate side of the cooperating peripheral element, while a low spot which interrupts the other contact surface spaces said other contact surface from that side of the cooperating peripheral element which is proximate thereto, thereby providing a driving connection at the initially engaged contact surface for driving the driven member by the driving member, said driving of the driven member by the driving member moving a low spot which interrupts the initially engaged contact surface into position spacing said initially engaged contact surface from that side of the cooperating peripheral element which is proximate thereto, and moving the other contact surface so that it is in position for engagement with that side of the cooperating peripheral element which is proximate thereto.

ing of the driven member by the driving member moving said other contact surface into engagement with that side of the cooperating peripheral element which is proximate thereto, so as to provide a driving connection at said other contact surface for continuing said driving of the driven member by the driving member, said driving of the driven member by the driving member then moving a low spot which interrupts the initially engaged contact surface into position spacing said initially engaged contact surface from that side of the cooperating peripheral element which is proximate thereto, thereby disconnecting the driving connection at said initially engaged contact surface, and the aforesaid actuating means continuing said relative axial shifting of the driving and driven members so as to disengage the driving connection at said other contact surface while the said low spot which interrupts the initially engaged contact surface is in position spacing said initially engaged contact surface from that side of the cooperating peripheral element which is proximate thereto.

9. In combination, transmission elements comprising a driving member and a driven member, a pair of contact surfaces on one of said elements, said surfaces being each interrupted by one or more low spots, actuating means for relatively axially shifting the transmission elements for initially engaging one or the other contact surface with the other transmission element for driving the driven member by the driving member, and means for periodically operating the actuating means independently of driving and driven movement of the transmission elements, said driving of the driven member by the driving member moving a low spot of the initially engaged contact surface into position spacing said initially engaged contact surface from the other transmission element, and moving the other contact surface so that it is in position for engagement with the other transmission element.

10. In combination, transmission elements comprising a driving member and a driven member, a pair of contact surfaces on one of said elements, said surfaces being each interrupted by one or more low spots, and actuating means for relatively axially shifting the transmission elements for initially engaging one or the other contact surface with the other transmission element, while a low spot of the other contact surface spaces said contact surface from the other transmission element, thereby providing a driving connection at the initially engaged contact surface for driving the driven member by the driving member, said driving of the driven member by the driving member moving said other contact surface into engagement with the other transmission element, so as to provide a driving connection at said other contact surface for continuing driving of the driven member by the driving member, said driving of the driven member by the driving member then moving a low spot of the initially engaged contact surface into position spacing said initially engaged contact surface from the other transmission element, thereby discontinuing the driving connection at said initially engaged contact surface, and the aforesaid actuating means continuing said relative axial shifting of the driving and driven members so as to disengage the driving connection at said other contact surface while the said low spot of the initially engaged contact surface is in position spacing said initially engaged contact surface from the other transmission element.

11. In combination, transmission elements, a driving connection between said elements adapted for engagement by relatively axially shifting said elements in one direction or the other, the engaged driving connection driving said elements one by the other, said driving of the elements one by the other relatively positioning the same for disengaging the driving connection by continued relative axial shifting of said elements, and actuating means for relatively axially shifting the transmission elements for engaging the driving connection and for then continuing said relative axial shifting for disengaging the driving connection.

12. In combination, transmission elements, a driving connection between said elements adapted for engagement by relatively axially shifting said elements in one direction or the other, the engaged driving connection driving said elements one by the other, said driving of the elements one by the other relatively positioning the same for disengaging the driving connection by continued relative axial shifting of said elements, actuating means for relatively axially shifting the transmission elements for engaging the driving connection and for then continuing said relative axial shifting for disengaging the driving connection, and means operative responsive to disengagement of the driving connection for arresting movement of that transmission element which has been driven by the other transmission element.

13. In combination, transmission elements comprising a rotary driving element and an oscillatory driven element shiftable transversely of its axis, actuating means for transversely shifting the driven element in one direction or the other for initially engaging and turning the driven element by the driving element, said turning of the driven element by the driving element causing relative displacement of said elements tending to disengage the same, the actuating means continuing said transverse shifting of the driving element subsequent to said initial engagement so as to maintain engagement and turning of the driven element by the driving element, and means for limiting said transverse shifting of the driven element whereby said relative displacement of the driving and driven elements disengages the same.

14. In combination, transmission elements comprising a rotary driving element and an oscillatory driven element shiftable transversely of its axis, actuating means for transversely shifting the driven element in one direction or the other for initially engaging and turning the driven element by the driving element, said turning of the driven element by the driving element causing relative displacement of said elements tending to disengage the same, the actuating means continuing said transverse shifting of the driven element subsequent to said initial engagement so as

to maintain engagement and turning of the driven element by the driving element, and means for limiting said transverse shifting of the driven element whereby said relative displacement of the driving and driven elements disengages the same and positions the driven element for reengagement by the driving element when the driven element is transversely shifted in the opposite direction.

15. In combination, transmission elements comprising a rotary driving element and an oscillatory driven element shiftable transversely of its axis, actuating means for transversely shifting the driven element in one direction or the other for initially engaging and turning the driven element by the driving element, said turning of the driven element by the driving element causing relative displacement of said elements for disengaging the same, and means for arresting turning of the driven element upon its disengagement from the driving element.

16. In combination, transmission elements comprising a rotary driving element and an oscillatory driven element shiftable transversely of its axis, actuating means for transversely shifting the driven element in one direction or the other for initially engaging and turning the driven element by the driving element, said turning of the driven element by the driving element causing relative displacement of said elements for disengaging the same, and means for arresting turning of the driven element upon its disengagement from the driving element; said arrested turning of the driven element positioning it for reengagement by the driving element when the driven element is transversely shifted in the opposite direction.

17. In combination, transmission elements comprising a rotary driving element and an oscillatory driven element shiftable transversely of its axis, actuating means for transversely shifting the driven element in one direction or the other for initially engaging and turning the driven element by the driving element, said turning of the driven element by the driving element causing relative displacement of said elements tending to disengage the same, the actuating means continuing said transverse shifting of the driven element subsequent to said initial engagement so as to maintain engagement and turning of the driven element by the driving element, means for limiting said transverse shifting of the driven element whereby said relative displacement of the driving and driven elements disengages the same, and means for arresting turning of the driven element upon its disengagement from the driving element, said arrested turning of the driven element positioning it for reengagement by the driving element when the driven element is transversely shifted in the opposite direction.

DELOS E. MARSH.
